UNITED STATES PATENT OFFICE.

ALFRED F. REILLY, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS.

DESIGN FOR A SALT OR PEPPER SHAKER.

Application filed May 28, 1928. Serial No. 26,887. Term of patent 3½ years

To all whom it may concern:

Be it known that I, ALFRED F. REILLY, a citizen of the United States, residing at Attleboro, in the county of Bristol and State of Massachusetts, have invented a new, original, and ornamental Design for Salt or Pepper Shaker, of which the following is a specification, reference being had to the accompanying drawing, forming part thereof.

Referring to the drawing.

Fig. 1 is an elevation of a salt or pepper shaker, showing my new design.

Fig. 2 is a top plan view of the same.

I claim:

The ornamental design for a salt or pepper shaker, as shown.

ALFRED F. REILLY.
